UNITED STATES PATENT OFFICE

JAMES J. HENNESSY, OF NEW YORK, N. Y.

JOURNAL LUBRICATOR

Application filed August 15, 1927. Serial No. 212,916.

My invention relates to lubricators such as are adapted particularly for use on railway rolling stock and in which the play of the journals in their boxes is utilized to operate a pump to elevate lubricant from a reservoir to the journal. Lubricators of this type are illustrated in various patents issued to me such, for instance, as No. 1,412,741 issued April 11, 1922 and improved lubricators of this type are disclosed in my copending applications Serial No. 742,253 filed October 7, 1924 and Serial No. 107,654 filed May 8, 1926 and patented March 12, 1929, Nos. 1,704,743 and 1,704,742 respectively.

In order to insure adequate lubrication of the journal under adverse conditions, such as cold weather, slow speed and slight play of the journal in its box, it is necessary to provide a pump of sufficient capacity to function properly under these conditions. Obviously, when conditions are more favorable, such as warm weather, high speed, and substantial play of the journal in its box, the same pump will feed a surplus amount of lubricant to the journal which will be wasted by centrifugal discharge from the journal. It is the main object of my invention to eliminate such waste.

Lubricators of this type utilize the ordinary cotton waste or other packing for uniformly distributing the lubricant to a large area of the journal and it is a further object of my invention to insure adequate distribution of lubricant by capillary attraction through such waste or packing.

Additional objects of my invention are to provide improvements in a lubricator device whereby the same may be more readily manufactured, assembled, filled at intervals and inspected.

These and other detailed objects of my invention are attained by the structure illustrated in the accompanying drawings in which—

Figure 1 is a vertical longitudinal section through my improved lubricator and showing an adjacent portion of the wheel and journal with which the lubricator is assembled.

Figure 2 is a vertical transverse section taken on line 2—2 of Figure 1.

Figures 3, 4 and 5 are detail sections taken substantially on the lines 3—3, 4—4, and 5—5 of Figure 1.

The lubricator illustrated is designed for use in locomotive journal boxes and comprises a body portion or cellar 1 which takes the place of the ordinary cellar and includes a lubricant reservoir 2. The inner end wall 3 of this body is shaped to fit about the journal A with which it is assembled. A sub-cell 4 is yieldingly supported upon a horizontal wall of the body by means of spring 5 and the end and side walls 6 and 7, respectively, of this sub-cell have their upper edges shaped to engage the journal A. The sub-cell includes a chamber 8 in which is slidably mounted a contact rod 9 which projects through a slot in body wall 3 and is adapted to be reciprocated by the hub H of the wheel and by a spring 10 in the sub-cell. A pump member 11 is fitted into chamber 8 and is provided with suitable passages 12 and 13 provided with check valves 14 and 15, respectively. It will be understood that the reciprocal movement of the pump piston 16 in the pump chamber 17 will force lubricant from the reservoir 2 up through passages 12 and 13 into the chamber 8 and into the upwardly extending conduit 18 which terminates in a discharge opening at the face of the journal 80 to be lubricated.

Slidable in conduit 18 is a plunger 19 having an aperture from top to bottom which permits the passage therethrough of a thin jet of oil. When the pressure in chamber 8 and conduit 18 reaches a predetermined point, plunger 19 is lifted from the bottom of conduit 18 and uncovers one or more outlets 20 provided in the side of conduit 18 and permits the flow of lubricant to that portion of the sub-cell which is outside of chamber 8. It will be seen that a pump, which is of sufficient capacity to insure a supply of lubricant to the journal under all conditions, may be used without necessarily resulting in an over-supply of lubricant when the conditions tend to produce the freest pumping operation, as any surplus lubricant will be readily discharged through the by-pass outlets 20. A pin α serves to prevent the loss of plunger 19. 100

Variations in the weight of plunger 19 and in the size of its aperture and of the holes 20 in chamber 8 enable me to control the amount of lubricant supplied to the journal and to the waste.

5 A perforated member 21 in sub-cell 4 serves as a support for waste, elevating the latter above the bottom of the sub-cell. The sides 7 of the sub-cell are provided with drainage holes 22 through which the lubricant, after rising above the level of the bottom of the waste, may flow back to the reservoir 2. This construction insures the application of lubricant to the lower portion of the waste at all times so that all of that portion of the waste which is in contact with the journal will be supplying lubricant to the journal by capillary attraction in the usual manner.

20 In order to facilitate the application and removal of the pump and sub-cell, I retain the pump and sub-cell in position by means of a removable cover 23 on the outer end of the body of the reservoir. The lower portion of this cover has depending and laterally extending lugs 24 adapted to slide beneath the top wall 28 of the reservoir 2, this wall being recessed as indicated at 26 (Figure 3) to permit the insertion and removal of lugs 24. When the cover is retracted from its normal position, lugs 24 serve to prevent upward movement of the cover from the position shown in Figure 1. To hold the cover against lateral movement from its proper position, 35 I provide cover 23 with an inclined sleeve 27 which is adapted to receive a spring pressed pin 29 which will project below the cover and engage the inner face of the end wall of the reservoir. The handle 30 on the outer end of pin 29 affords a fingerhold for withdrawing the pin and permitting the cover 23 to be moved to the right to the position in which its lugs may be passed through openings 26.

The reservoir 2 is filled through a suitable 45 opening which is provided with a closure 31 adapted to project downwardly through the opening in order to reduce loss by splashing of the lubricant in the reservoir. This closure is retained in the cover by a lug 32 which will engage the bottom of the cover except when it is turned from the position shown in Figure 1 so that it will be in vertical alignment with the slot 33 provided in the side of the opening for the closure. A chain 34 or similar fastening device tends to hold the lug 32 in the position shown in Figure 1. This arrangement prevents the loss of the cover along the right-of-way due to the jarring of the driver box.

55 By providing a lubricant bath for the lower portion of the waste there is no danger of the waste ever drying out and I can therefore use more restricted passageways for the lubricant through the pump and the conduit leading to the journal which could not be done

with my earlier by-pass structures, set forth in the applications referred to above, which relied upon the discharge of surplus lubricant through the journal conduit in order to saturate the body of waste.

70 My structure preferably includes two or more spaced vertical ribs 36 extending transversely of sub-cell 7 to the height of outlet holes 22. These ribs are for the purpose of restricting the spread of the oil throughout the lower portion of the waste and before the oil has reached the level of holes 22. This will lessen the amount of oil which is wasted by being thrown off of the journal at its ends. The level of the free oil will not rise above holes 22, but waste above these holes and to the sides of ribs 36 will be saturated by capillary attraction sufficiently to apply lubricant over the entire lower surface of the journal. 75 By varying the distance between ribs 36 and by varying the height of these ribs, the application of oil to the journal may be controlled. It will be understood that journals operating under different loads and at different speeds will be best served by providing a sub-cell construction in which the features just discussed are designed for the most efficient application of the lubricant.

80 The cover retaining elements eliminate the necessity of any machine work on the body except the provision of the tapped hole for the drain 35 and the covers 23 can be made the same size for all of my devices whereas formerly, because of the method of holding the cover in place, it was necessary to adapt the cover and adjacent portion of the cellar for different sizes or styles of driving boxes.

85 Obviously the advantages of my invention can be attained by modifying the details of construction and I contemplate the exclusive use of all such variations of the described device as fall within the scope of my claims.

90 I claim:

1. In a journal lubricator, a reservoir, a waste-holding sub-cell therein, a waste support in said sub-cell, a lubricant conduit in said sub-cell adapted to lead to the journal to be lubricated, and means in said conduit for by-passing surplus lubricant from said conduit independently of said support or waste therein to the interior of said sub-cell outside of said conduit.

110 2. In a journal lubricator, a lubricant reservoir, a sub-cell therein, a waste support in said sub-cell and spaced from the bottom thereof, a lubricant conduit in said sub-cell adapted to lead from said reservoir to the journal to be lubricated independently of waste in said support, and means in said conduit providing a by-pass therefrom to the interior of said sub-cell below said waste support.

115 3. In a journal lubricator, a lubricant reservoir, a sub-cell therein, a waste support in said sub-cell and spaced from the

bottom thereof, a lubricant conduit in said sub-cellар adapted to lead from said reservoir to the journal to be lubricated independently of waste in said support, means in said conduit providing a by-pass therefrom to said sub-cellар below said waste support, and an outlet in said sub-cellар above the bottom of said waste support and below the discharge end of said conduit.

19. 4. In a journal lubricator, a reservoir, a waste-holding sub-cellар therein, a lubricant conduit in said sub-cellар adapted to lead to the journal to be lubricated, a pump for forcing lubricant from said reservoir through said conduit, and a by-pass from said conduit to the portion of said sub-cellар outside of said conduit, said by-pass being adapted to function upon the presence of a predetermined pressure on the lubricant in said conduit.

23. 5. In a journal lubricator, a reservoir, a waste-holding sub-cellар therein, a lubricant conduit in said sub-cellар adapted to lead to the journal to be lubricated and terminating in a passage-way having a discharge end and an outlet through one side spaced from said end and leading to said sub-cellар outside of said conduit, and an apertured plunger movably mounted in said passage-way and normally obstructing said outlet but movable to a position in which it does not obstruct said outlet.

25. 6. In a journal lubricator, a reservoir, a waste-holding sub-cellар therein, a lubricant conduit in said sub-cellар adapted to lead to the journal to be lubricated and terminating in an upright passage-way having a discharge opening at its upper end, a plunger slidably mounted in said passage-way and provided with a vertical aperture, there being an outlet through the side of said passage-way leading to said sub-cellар outside of said conduit and adapted to be uncovered by said plunger when the latter is raised in said passage-way.

45. 7. In a journal lubricator, a lubricant reservoir having a filling opening in its top wall, a removable closure for said opening extending downwardly therethrough and having a lateral projection for engaging the under surface of said top wall, there being a groove at one side of said opening for permitting passage of said projection when aligned therewith, and a connection between said closure and said reservoir at one side of said opening for normally holding said projection out of alignment with said groove.

60. 8. In a journal lubricator, a lubricant reservoir, a sub-cellар therein, a waste support in said sub-cellар and spaced from the bottom thereof, a lubricant conduit in said sub-cellар adapted to lead to the journal to be lubricated, means in said conduit providing a by-pass to said sub-cellар below said waste support, an outlet in said sub-cellар

above the bottom of said waste support and below the discharge end of said conduit, and means in said sub-cellар for restricting the spread of lubricant below said outlet.

9. In a journal lubricator, a lubricant 70 reservoir, a sub-cellар therein, a waste support in said sub-cellар and spaced from the bottom thereof, a lubricant conduit in said sub-cellар adapted to lead to the journal to be lubricated, means in said conduit providing a by-pass to said sub-cellар below said waste support, an outlet from said sub-cellар above the bottom of said waste support, and upstanding transverse partitions between said outlet and the ends of said sub-cellар.

10. In a journal lubricator, a reservoir, a sub-cellар elevated above the body of said reservoir and adapted to hold lubricant to a certain level, a waste support in said sub-cellар below said level, a lubricant conduit 85 leading from said reservoir to the journal to be lubricated, and means for by-passing surplus lubricant from said conduit to said sub-cellар and from said sub-cellар to said reservoir.

In testimony whereof I hereunto affix my signature this 22 day of July, 1927.

JAMES J. HENNESSY.
